CLAIM

The ornamental design for a lighting fixture, as shown and described.

DESCRIPTION

FIG. 1 is a bottom perspective view of the lighting fixture according to a first embodiment;

FIG. 2 is a top perspective view of the lighting fixture;

FIG. 3 is a right side elevation view of the lighting fixture;

FIG. 4 is a left side elevation view of the lighting fixture;

FIG. 5 is a front end elevation view of the lighting fixture;

FIG. 6 is a rear end elevation view of the lighting fixture;

FIG. 7 is a bottom plan view of the lighting fixture;

FIG. 8 is a top plan view of the lighting fixture;

FIG. 9 is a bottom perspective view of the lighting fixture according to a second embodiment;

FIG. 10 is a top perspective view of the lighting fixture of FIG. 9;

FIG. 11 is a right side elevation view of the lighting fixture of FIG. 9;

FIG. 12 is a left side elevation view of the lighting fixture of FIG. 9;

FIG. 13 is a front end elevation view of the lighting fixture of FIG. 9;

FIG. 14 is a rear end elevation view of the lighting fixture of FIG. 9;

FIG. 15 is a bottom plan view of the lighting fixture of FIG. 9;

FIG. 16 is a top plan view of the lighting fixture of FIG. 9;

FIG. 17 is a bottom perspective view of the lighting fixture according to a third embodiment;

FIG. 18 is a top perspective view of the lighting fixture of FIG. 17;

FIG. 19 is a right side elevation view of the lighting fixture of FIG. 17;

FIG. 20 is a left side elevation view of the lighting fixture of FIG. 17;

FIG. 21 is a front end elevation view of the lighting fixture of FIG. 17;

FIG. 22 is a rear end elevation view of the lighting fixture of FIG. 17;

(Continued)

FIG. 23 is a bottom plan view of the lighting fixture of FIG. 17;
FIG. 24 is a top plan view of the lighting fixture of FIG. 17;
FIG. 25 is a bottom perspective view of the lighting fixture according to a fourth embodiment;
FIG. 26 is a top perspective view of the lighting fixture of FIG. 25;
FIG. 27 is a right side elevation view of the lighting fixture of FIG. 25;
FIG. 28 is a left side elevation view of the lighting fixture of FIG. 25;
FIG. 29 is a front end elevation view of the lighting fixture of FIG. 25;
FIG. 30 is a rear end elevation view of the lighting fixture of FIG. 25;
FIG. 31 is a bottom plan view of the lighting fixture of FIG. 25;
FIG. 32 is a top plan view of the lighting fixture of FIG. 25;
FIG. 33 is a bottom perspective view of the lighting fixture according to a fifth embodiment;
FIG. 34 is a top perspective view of the lighting fixture of FIG. 33;
FIG. 35 is a right side elevation view of the lighting fixture of FIG. 33;
FIG. 36 is a left side elevation view of the lighting fixture of FIG. 33;
FIG. 37 is a front end elevation view of the lighting fixture of FIG. 33;
FIG. 38 is a rear end elevation view of the lighting fixture of FIG. 33;

FIG. 39 is a bottom plan view of the lighting fixture of FIG. 33; and,
FIG. 40 is a top plan view of the lighting fixture of FIG. 33.
